UNITED STATES PATENT OFFICE

114,572

DESIGN FOR A SCALE

Burns S. Watling, Chicago, Ill., assignor to Watling Scale Company, Chicago, Ill., a corporation of Illinois

Application March 3, 1939, Serial No. 83,310

Term of patent 14 years

To all whom it may concern:

Be it known that I, Burns S. Watling, a citizen of the United States, residing at Chicago, in the county of Cook and State of Illinois, have invented a new, original, and ornamental Design for a Scale, of which the following is a specification, reference being had to the accompanying drawing, forming part thereof.

Figure 1 is a front elevation of the scale embodying my new design.

Figure 2 is a side elevation of the same.

I claim:

The ornamental design for a scale, substantially as shown.

BURNS S. WATLING.
